(**) Term: **14 Years**

CLAIM

(21) Appl. No.: **29/158,204**

The ornamental design for a remote control device, as shown and described.

(22) Filed: **Mar. 29, 2002**

DESCRIPTION

(51) LOC (7) Cl. **14-03**

FIG. 1 is a perspective view of a remote control device;

(52) U.S. Cl. **D14/218**

FIG. 2 is a front elevational view thereof;

(58) Field of Search D14/174, 217,

FIG. 3 is a right side elevational view thereof;

D14/218, 137-139, 151, 191-193, 124,

FIG. 4 is a left side elevational view thereof;

299, 167-168; D13/168, 162-164; D21/512-517,

FIG. 5 is a rear elevational view thereof;

566; D10/104, 106; 455/352-355, 151.1-151.4;

FIG. 6 is a top plan view thereof; and,

348/114, 734

FIG. 7 is a bottom plan view thereof.

The broken line showing of environmental structure is for illustrative purposes only and forms no part of the claimed design.
